United States Patent Office

Des. 186,018
Patented Sept. 1, 1959

186,018

CLOTHESPIN

John Duda, Chicago, Ill.

Application March 27, 1959, Serial No. 55,222

Term of patent 14 years

(Cl. D17—6)

FIG. 1

FIG. 2

FIG. 3

FIG. 4

FIG. 5

Figure 1 is a front view of a clothespin showing my new design.

Figs. 2, 3, 4 and 5 are side, rear, top and bottom views thereof, respectively.

I claim:

The ornamental design for a clothespin, as shown.
